UNITED STATES PATENT OFFICE.

JOSEPH JULIUS MÜLLER, OF LUCERNE, SWITZERLAND.

BICYCLE-SUPPORT.

SPECIFICATION forming part of Letters Patent No. 484,941, dated October 25, 1892.

Application filed January 12, 1892. Serial No. 417,859. (No model.) Patented in Germany June 7, 1891, No. 59,865, and in England June 8, 1891, No. 9,695.

To all whom it may concern:

Be it known that I, JOSEPH JULIUS MÜLLER, joiner, a citizen of the Republic of Switzerland, of Lucerne, in the Republic of Switzerland, at present residing in Copenhagen, in the Kingdom of Denmark, have invented certain new and useful Improvements in Supports for Bicycles, (for which I have obtained Letters Patent in Germany, No. 59,865, dated June 7, 1891, and in England, No. 9,695, dated June 8, 1891,) of which the following is a specification.

The object of my invention is to provide a new and improved support in which bicycles can be so held as not to injure the rubber tires and to permit of turning the wheels for oiling and cleaning them.

The invention consists in a bicycle-support composed of two united standards, a vertically-adjustable plate on each standard, which plates are provided at their upper ends with forks for receiving the crank-shaft, a brace resting on the support for supporting the front end of the bicycle-frame, and a hook-bar on said support for embracing and holding the crank-shaft in place on the upper ends of the vertically-adjusted plates.

The invention also consists in the construction and combination of parts and details, which will be fully described hereinafter, and finally pointed out in the claims.

In the accompanying drawings, Figure 1 is a perspective view of my improved bicycle-support. Fig. 2 is a similar view, on an enlarged scale, showing part of a safety-bicycle held in the same. Fig. 3 is a detail view of the extensible sliding plate. Fig. 4 is a perspective view of the roller-frame. Fig. 5 is a detail perspective view of the spring used to hold down the front wheel.

Similar letters of reference indicate corresponding parts.

The support consists of two side pieces or standards *a*, which are flared outward at their lower ends to form legs or feet, and said standards are connected with each other by transverse bolts *b*. To each standard a sliding plate *c'* is fitted, which can be held at any desired elevation by a binding-screw *d*, the threaded part of which is screwed into the side of the standard, and which binding-screw

passes through a vertical slot *c*³ in the sliding plate *c'*. The sliding plates *c'* slide in recessed parts in the outer faces of the standards and are guided by the side edges of the recesses. The upper ends of the sliding plates *c'* form forks *b'* for receiving the crank-shaft of the bicycle, or the bearings for said crank-shaft. For holding said bearings the supports *p* are provided on the outer side with upwardly-projecting flanges *q*, which prevent lateral movement of said crank-shaft when in the forks, as the flanges project above the sides of the bearings of the crank-shaft.

In the drawings, *g* is the crank-shaft; *h*, the cranks; *i*, the sprocket-wheel on the crank-shaft, and *j'* part of the frame of the Safety bicycle. The bolts *b*, connecting the standards *a*, are secured in one standard and at the outer end are provided with nuts, so as to permit the adjusting of the standards at a greater or less distance from each other, according to the length of the crank-shaft of the bicycle to be held. As the plates *c'* can be adjusted vertically, the support can be adjusted in height or width to suit any wheel. In case both wheels of the bicycle are to be held above the floor this can be accomplished by means of the rod *k*, which is forked at both ends, the prongs of the lower fork embracing the lower transverse bolt *b* of the support and the upper fork engaging the frame of the bicycle at the proper point, in safety-bicycles at the angle formed by the backbone and steering-head. The said rod *k* consists of two parts, one of which can slide in the other, one of them being provided with a binding-screw, so as to adjust said rod to any desired length. The upper bolt of the support carries a rocking holding device composed of two parts *l'* *l*², the part *l'* being provided at its upper end with a hook *m*. The two parts *l'* *l*² are held together by means of a binding-screw *n* in the piece *l'*, as shown in Fig. 2, said screw passing through a slot of the part *l*². Those edges of the parts *l'* *l*² facing each other are provided with teeth which can interlock, and thus serve to make the connection between the parts *l'* and *l*² more rigid. After the parts *l'* and *l*² have been loosened as much as desired, the hook *m* is passed over the crank-shaft and then the

parts v and v' are adjusted at the proper length and drawn together, whereby the hook m securely holds the bicycle on the support.

In case a tricycle is to be held the transverse rod which is below the rear axle of the tricycle is placed into the forks p . In case a tricycle or ordinary or high wheel is to be held the plates c' are replaced by the plates c^2 , (shown in Fig. 3,) provided at their upper ends 10 with a tubular extension r , adapted to receive the sliding rod t , which can be locked at any desired elevation by means of a screw s . The fork p' is formed at the upper end of said rod t , and at said fork the inclined flanges q' 15 q' are formed. When ordinary are to be held, the upper bolt b , connecting the standards a , is removed, so as to permit the turning of the larger wheels. It is evident that with this stand the rubber tires of the cycles 20 are not injured, as no part of the weight of the cycle rests upon the same. The driving-wheel is at all times held clear from the floor and can be turned for the purpose of examining, repairing, or oiling the same.

25 With this device the safety-bicycle can be used as a home trainer, in which case a frame y , provided with grooved rollers $v v$, is placed under the rear wheel, which rests on said rollers. When the person occupies the wheel, 30 the weight of said person swings the same toward the rear until the tire of the rear wheel is in contact with the rollers $v v$, whereby the desired friction is produced without in any way injuriously affecting the tire, whether 35 the same be a solid tire, cushioned tire, or pneumatic tire. If, however, the pressure upon the rollers $v v$ is too great, the tension-spring shown in Fig. 5 can be used, which consists of a spring x , provided at one end 40 with a hook z , and at the other end with a prong z' , which prong, if desired, may be provided with screw-threads. The prong z' is secured in the floor either by driving it in or screwing it in, and then the hook z is engaged 45 with the rim of the front wheel and draws the same downward, thereby raising the rear wheel more or less to prevent too much friction between the tire of the rear wheel and the rollers $v v$.

Having thus described my invention, I claim as new and desire to secure by Letters Patent—

1. In a bicycle-support, the combination, with two standards, of vertically-adjustable plates on the same provided at their upper ends with forks for receiving the crank-shaft of a cycle and means for adjusting said standards a greater or less distance from each other, substantially as set forth. 55

2. In a bicycle-support, the combination, with two standards, of vertically-adjustable plates on the same provided at their upper ends with forks for receiving the crank-shaft of a bicycle and of a rod having its lower end supported by the standard and its upper end 65 engaging the front part of the bicycle, substantially as set forth.

3. In a bicycle-support, the combination, with two standards, of vertically-adjustable plates on the same provided at their upper 70 ends with forks for receiving the crank-shaft of the bicycle and an extensible swinging hook-bar on a bolt uniting the standards, substantially as set forth.

4. In a bicycle-support, the combination, with two standards, of vertically-sliding plates in the same provided at their upper ends with forks for receiving the crank-shaft of the cycle, a swinging extensible bar composed of two sections mounted on one of the bolts uniting the standards, and a hook on the upper end of said extensible bar, substantially as set forth. 80

5. In a bicycle-support, the combination, with two standards, of vertically-adjustable plates on the same, a tubular extension on each plate, a rod held in each extension and provided at its upper end with a fork, and a screw for locking each rod in the extension, substantially as set forth. 90

In testimony that I claim the foregoing as my invention I have signed my name in presence of two subscribing witnesses.

JOSEPH JULIUS MÜLLER.
